UNITED STATES PATENT OFFICE.

FRED A. SCHWAB, OF BUTTE, MONTANA.

VALVE CONSTRUCTION.

Original application filed April 28, 1920, Serial No. 377,254. Divided and this application filed December 8, 1922. Serial No. 605,737.

To all whom it may concern:

Be it known that I, FRED A. SCHWAB, a citizen of the United States, residing at Butte, in the county of Silverbow and State of Montana, have invented certain new and useful Improvements in Valve Construction, of which the following is a specification:

This case is a division of applicant's prior case, No. 377,254, filed April 28th, 1920.

The invention relates to carburetors and valves, particularly to means suitable for use to control the flow of two different fuels to and from a carburetor bowl, and to a suitable mixing element. That is to say, it is an aim to provide a valve of a novel form by which feed of fuel to two separate carburetor bowls may be alternatively controlled, and whereby fuel from these bowls may also be supplied to a common conduit or cut off therefrom. It is also an aim of the invention to construct such a device which, in addition to the functions before named, will also serve as a complete cut-off of two fuel supplies to the carburetor, and of the outlet from the carburetor. It is an additional object to attain the ends named by means of a single valve element of comparatively simple form which may be operated for the different functions by one control lever.

Additional objects, advantages and features of invention will appear from the construction, arrangement and combination of parts hereinafter described and shown in the drawings, wherein,

Figure 1 is a longitudinal sectional view of the valve and its housing, in one possible embodiment,

Fig. 2 is a side view of the valve plug alone,

Fig. 3 is a top view of a carburetor double bowl element, and valve housing involved in the invention,

Fig. 4 is a cross section at one of the fuel supply connections on the bowl,

Fig. 5 is a similar view centrally of Fig. 3.

There is illustrated a base element 10 of a carburetor having two reservoir bowls 11 therein, adapted to contain two different fuels supplied thereto through respective fuel connections 12 at one side of the bowl. Between the connections 12 and the bowls 11, the body of the bowl is enlarged as at 13, so as to enable the formation of a horizontal

conical bore 14 extending past the bowls 11 and the connections 12. Opening from each connection 12 to the bore 14, there are conduit passages 15, and alined with these at the opposite side of the bore, there are continuation passages 16 which extend into float-mounting lugs 17, stopping short of the bowls 11 and being adapted to be drilled simultaneously with the passages 15, through the connections 12. Extending downwardly through the lug there are valve guide passages 18, in which valves 19 are slidable, arranged to close the fuel feed at the lower part, after any suitable manner. Immediately above the point of closure, passages 20 open from the valve passage 18 into the wells 11. Any usual float construction 21 may be utilized, connected with the valves 19 in a suitable way to effect opening of the valves when the floats become lowered, and closure of the valve when the floats are raised. In addition to the passages 16 and 20 opening from the wells 11 to the bore 14, passages 22 also open from the wells into the bore 14, the last named passages being formed inwardly of the passages 16. The passages 22 are spaced equally from the mid length of the bore and medially of the bore there is formed a vertical passage 23 opening from the bore through the top face 24 of the enlargement 13 before mentioned.

Any usual connections or conduits may be associated with the passage 23 to conduct fuel therefrom to a mixing chamber of the carburetor, or other devices as may be involved in the carburetor or charge forming means, one means being formally illustrated at 25 in Fig. 1, the details of which form no essential part of the present invention. Fitted snugly in the bore 14, there is a plug valve 26 having passages 27 formed in respective planes at right angles to the axis of the plug and alined with the passages 16 being of rectilinear form extending diametrically through the plug, these passages being in respective longitudinal planes at right angles to each other,—that is to say, the orifices of the two passages are spaced circumferentially of the plug 90 degrees. Inwardly of these passages and circumscribing the plug in a plane at right angles to its axis, there are annular grooves 28, alined with the passages 22. From each groove, there extends longitudinally inward upon the plug a channel 30, stopping short of the

- other groove, the channel 30 from each groove being spaced circumferentially of the plug 90 degrees from the adjacent diametrical passage 27. With this relation of the parts, when one passage 27 is in position aligned with the passages 15 and 16 of the valve cage, the respective channel 20 from the next adjacent groove 28 may be located at the upper side of the plug, and in communication with the outlet passage 23, whereby not only is fuel admitted to the wells 11, but may pass from the wells by way of the passage 22, groove 28, channels 30 and passage 23, to the charge forming means proper.
- 15 With the port elements spaced as indicated, a one-eighth turn of the valve from open position with respect to either well 11 will effect cut-off of both fuel feeds, and both conduits from the wells to the charge forming means. Assuming the valve to be in position open for supply of fuel to one well, and passage of fuel therefrom to the charge forming means at the passage 23, a quarter turn of the valve in the proper direction will close off both fuel supply and charge supply from one well, and establish operative conditions with the other.
- In carburetors and the like, this has the advantage that after cut-off of fuel supply to one well, the contents of that well will not be exhausted when fuel is being used from the other well, and at any time that it may be necessary to suddenly change from one fuel to another, there will always be fuel ready for instant use in the respective well, without requiring time for the well to be filled to a proper level before proper feed of fuel therefrom will be effected. Economy of fuel is thus effected in operation of engines in which two fuels are involved, and liability of leakage is also minimized. The plug valve 26 may be secured in the bore 14 in any customary way, and may be operated in any suitable manner. In the present instance, a washer 31 having a rectangular opening is fitted upon a rectangular tenon 32 at the small end of the plug, the washer being of a size to abut snugly against the adjacent face of the bowl casting, the plug being drawn snugly into the passage 14 by means of a nut 33 engaged upon the threaded portion 34 of the plug. The large end of the plug is also tenoned and may be fitted with a lever as at 35, in Fig. 1.
- 55 It is an advantage of the annular channels 28 that they will serve to collect sediment or water, which may be removed without taking down the carburetor, by simply loosening the plug valve 26.
- 60 The device is adapted to be constructed economically, and serves the double function efficiently.

What is claimed is:—

1. In a device of the character described, a plurality of fuel bowls and respective liquid

level controls, a plurality of liquid fuel sources, and a charge forming device, a valve case, conduits from the bowls to the valve case, a conduit from each fuel source to the valve case, and a conduit from the valve case to the charge forming device; and a single valve member operative in the case constructed and operable to form communication between any of the fuel sources and respective bowls alternately and between such respective bowl and the charge forming device and to positively close communication between the other bowl and fuel sources in respective positions of the valve, and in other positions to positively close communication between both bowls and all fuel sources.

2. A carburetor fuel supply and outlet control device comprising a body element having two bowls, a valve case element thereon, having a conical seat passage therein, a rotatable plug fitted to the seat passage, two main supply conduits opening through the case into said passage and having extensions opening from the passage at a distance from the said conduits, passages being formed in the plug positioned to connect respective conduits and their extensions alternately and being arranged to be both positioned out of connecting relation whereby positive cut-off of two supplies may be effected, separate bowl outlet conduits entering the said seat passage at points spaced longitudinally from the main conduits and spaced longitudinally from each other, and an outlet conduit opening from the seat passage between the conduits last named, said plug having passages formed therein separate from those herein first named, each adapted to form communication between one of the second named conduits and the outlet only when the adjacent main supply conduit and respective first named passage in the plug are in connecting relation, said extensions having communication with respective reservoirs at one side of the plug, and respective fluid-level-actuated means associated therewith to control flow of fuel to the reservoirs.

3. In an internal combustion engine the combination with two liquid fuel float chambers each having a fuel inlet duct, an outlet duct to the engine and a float and a valve controlled by the float to control the inlet duct, of a single valve member for positively closing both the inlet duct and the outlet duct of each chamber substantially simultaneously and the ducts of the two chambers alternately.

In testimony whereof I have affixed my signature in presence of two witnesses.

FRED. A. SCHWAB.

Witnesses:

ROBERT SMITH,
W. E. TUTTLE.

Certificate of Correction.

It is hereby certified that Letters Patent No. 1,545,284, granted July 7, 1925, upon the application of Fred A. Schwab, of Butte, Montana, for an improvement in "Valve Construction," were erroneously issued to the inventor, said "Schwab," whereas said Letters Patent should have been issued to the inventor, said *Schwab*, and *Robert Smith, of Butte, Montana*, said "Smith" being assignee of one-half interest in said invention, as shown by the records of assignments in this office; in view of the affidavit in the file, the inventor's name should read *Fredrick* instead of "Fred"; and that the said Letters Patent should be read with these corrections therein that the same may conform to the record of the case in the Patent Office.

Signed and sealed this 18th day of August, A. D. 1925.

[SEAL.]

KARL FENNING,
Acting Commissioner of Patents.
